UNITED STATES PATENT OFFICE.

ALLEN I. BLANCHARD, OF CHICAGO, ILLINOIS.

CASH-FARE-TICKET HOLDER AND CUTTER.

No. 892,121.

Specification of Letters Patent.

Patented June 30, 1908.

Application filed April 28, 1908. Serial No. 429,772.

To all whom it may concern:

Be it known that I, ALLEN I. BLANCHARD, a citizen of the United States, residing at Chicago, Cook county, Illinois, have invented certain new and useful Improvements in Cash-Fare-Ticket Holders and Cutters, of which the following is a specification.

My invention relates to holders and manipulators for cash fare tickets and the like, such as shown in my prior patent No. 818,996, issued to me on April 24, 1906, and the object thereof is to provide a novel and efficient device of this character capable not only of manipulating or executing the ticket according to the amount of cash fare paid by the passenger, but also of depositing and retaining in an automatic manner that portion of the ticket commonly known as the auditor's stub and remaining after that portion commonly known as the passenger's receipt has been handed to the passenger, with the result that the manipulating of the ticket and the depositing or retaining of the stubs thereof are performed by means of a single instrumentality or device. The ticket holder when not in use and carried in the pocket of the conductor is of a comparatively small size, being substantially of the same size as the bunch of cash fare tickets or slips which are carried therein in separate or loose form, but in use part of the holder is adapted to be drawn out partially so as to place the tickets in position to be acted upon by the cutter. The ticket is thereupon operated upon or manipulated and the stub left undisturbed in the holder, whereupon the said movable part of the holder is returned to its original position, with the result that the stub is deposited in the holder proper automatically and as an incident to the movement of said part. Whereas heretofore it was necessary for the conductors to remove the stubs from the holder by hand and place the same in their pocket or in their account book or other receptacle, the stubs in my ticket holder are left therein and are automatically deposited and retained so that at the end of his run, the conductor upon opening the holder to make up his accounts for the auditor, will find all of the stubs deposited therein. Moreover, provision is made for a visible manipulation of the ticket by exposing the large type or conspicuous value figures of such ticket at notches in the cutter, so that the conductor can readily move the cutter and execute the ticket with facility, besides

which provision is made on the ticket for different memoranda, such as indications of the stations between which the trip is made, the rate or amount of the fare, character of the fare, number of the train, date, etc., which memoranda is necessary in the making up by the conductor of his report for the auditor's use. Other features of advantage and utility in my ticket holder and also in the form of cash fare ticket or slip which is preferably employed therein will be apparent from the description hereinafter given. In view of the different functions performed by my ticket holder, the same may be designated a visible manipulating and automatic stub-depositing cash-fare ticket holder.

In the drawings, Figure 1 is a perspective of my ticket holder containing a bunch or supply of the cash fare tickets or slips and showing such holder in its compact or closed condition; Fig. 2 a similar view, but showing the holder in its open or extended condition and illustrating the manipulation or execution of a ticket; Figs. 3 and 4 perspectives of the two main portions, respectively, of the ticket holder; Fig. 5 a cross section of the ticket holder and tickets when the holder is in closed condition; Fig. 6 a similar view but with the ticket holder in open condition; Fig. 7 an end view of the ticket holder and tickets when the ticket holder is in open condition; Fig. 8 a section on the line 8 of Fig. 7; Fig. 9 a section on the line 9 of Fig. 7.

As hereinbefore stated, the cash fare tickets or slips used in connection with my ticket holder may be substantially the same as those of my prior patent aforesaid, but I prefer to employ with the particular construction of holder herein illustrated the form and arrangement of cash fare ticket shown in Figs. 1 and 2. This ticket is provided longitudinally at its central portion along or adjacent the line of severance with the three series of figures from "0" to "9", arranged in three divisions, representing dollars, dimes and cents, whereby when the ticket is severed longitudinally by the cutter hereinafter described, the severed edges of the two portions or halves will unalterably indicate the amount of cash fare paid. The series of figures just referred to are those in the larger and bold-faced type, which are immediately adjacent the severing line and coöperate with said cutter, but in addition I provide above said series of figures similar but less conspicuous series of figures parallel with and immediately

above said first named series, said last named figures being on that portion of the ticket which will eventually become the passenger's receipt, with the result that even though any 5 one or more of the tips of such portion of the ticket became detached or torn off, the receipt will nevertheless indicate the amount for which the ticket was executed. My present form of ticket also employs a number 10 of blank spaces for different memoranda to be inserted by the conductor upon making up his report to the auditor, such as the blanks for indicating the station from and the station to which the passenger made the 15 trip represented by the cash fare ticket, the blank for the train number, the blanks for the date, the blank for the rate or amount paid, and two separate blank spaces, one or the other of which is punched by the conductor 20 to indicate either regular or half fare, as the case may be. In addition, immediately below the series of more conspicuous figures representing dollars, dimes, and cents, blank spaces are left to enable the conductor while 25 or immediately after executing the ticket, to write therein (in the present instance through slits on the cutter) certain memoranda indicating the stations between which the trip is made and also the fact of the half fare rate, 30 if such it is. It will be understood that my present ticket is severable as usual into the two portions A and A¹, the former constituting the passenger's ticket or receipt which is handed to the passenger and the latter the 35 conductor's or auditor's stub, which, as hereinafter described, is automatically deposited and retained in the holder itself.

The ticket holder is formed essentially of two sliding or telescoping parts B and C, a 40 lid or cover D and a cutter E. The part C which is the sliding part, as respects the part B which is adapted to be held stationarily in the hand, may be termed the ticket receptacle, inasmuch as it is designed to receive 45 and hold a supply or bunch of the tickets such as shown in Fig. 1, these tickets being in loose form, that is, in separate slips or sheets. The outer edge of this receptacle is provided with a flange c of a height substantially equaling the thickness of the entire ticket holder and having its central portion cut away at c¹ to expose the outer edges of the tickets and thereby enable the conductor to readily pick up or grasp the uppermost 50 ticket in the process of manipulating the same. The flange c is continued partially along the opposite edges of the ends of the receptacle, thereby forming right-angle corners to receive and hold said supply of 55 tickets, all as clearly illustrated in Fig. 4 of the drawings. The inner longer edge of the receptacle is provided with an upturned right angle flange c², parallel with, but of less height than the opposite flange c, and such flange is 60 likewise continued to a slight extent along the 65

opposite edges of the ends of the receptacle. As a result, the receptacle is flanged on all of its sides excepting for portions c³ at the opposite ends thereof. These free edges of the ends of the receptacle are recessed at c⁴ for a 70 purpose hereinafter explained.

The holder proper marked B is provided with a flange b along its outer edge and extending at right angles partially along the edges of the opposite ends thereof and is also 75 provided with inturned flanges or tongues b¹ which, in the present instance, are stamped from the material of the holder itself and arranged adjacent the ends of the flanges b. These flanges b¹ form locking guides under 80 which the edges c³ of the ticket receptacle pass and by which such receptacle is held in telescoping and sliding coöperation with the holder proper, except when such receptacle is in a certain relative position permitting its 85 entire removal from the holder, as hereinafter explained. The receptacle C is, of course, slightly shorter than the ticket holder so as to be received by and to telescope within the latter, and when the device is in closed condition, as shown in Fig. 1, the corner portions of the flanges c are partially received within the upturned flanges b² at the extreme outer corners of the ticket holder B. 90

When the device is in closed, as well as 95 open position, the ticket receptacle is maintained in sliding or telescoping coöperation with the holder B by means of the tongues or flanges b¹, which overhang the edges c³ of the receptacle, preventing the latter from being 100 removed from the holder except when the receptacle is permitted to be drawn outwardly to its full or abnormal extent. However, the receptacle is limited in its telescoping or sliding movement in suitable manner—in the present instance by means of the inturned ends g of a spring G which holds the 105 cover D in place upon the tickets with a yielding pressure. These spring ends enter through slots b³ in the base of the end flanges b and in the path of movement of the end 110 portions of the flange c². When the ticket receptacle is drawn outwardly, it is limited by the contact of the ends c⁵ of said end flanges c² with said wire ends g and inasmuch 115 as, at such limit of movement, the ends c³ of the ticket receptacle are still beneath the locking flanges b¹, the receptacle is permitted to slide freely within limits, but it is impossible to remove such receptacle bodily from 120 the holder proper until said wire ends are removed, whereupon the ticket receptacle may be drawn outwardly to a greater extent until said recesses c⁴ register with the flanges b¹, whereupon said ticket receptacle and tickets 125 may be removed bodily from the holder proper.

The cover D consists of a plate hinged to the upper edges of the side flange b upon the spring wire G as an axis, and the cutter E is 130

hinged to and caused to slide upon a rod H secured to the outer or free side of said cover. This cover is provided along its free side with a right angle flange d extending substantially the entire length of such cover and in the present instance stamped from the metal or material of the cover itself. The arrangement is such that the lower edge of this flange d and the cutter when in normal position 19 resting upon the tickets, are in the same plane as illustrated in Figs. 5 and 6. If desired the ends of the cover may be provided with depending flanges d¹.

The cutter E is provided along its cutting 15 or straight edge with the two severing notches e and e¹ which extend inwardly into the body of the cutter and by preference also extend outwardly or beyond the tearing edge, inasmuch as each notch is provided with a pair of 20 projecting points e², as clearly illustrated in Fig. 3, the purpose of which will be apparent from the description hereinafter given. The cutter is also provided with the two longitudinal slots e³ for the purpose of enabling 25 the conductor, while executing the ticket, to write his memoranda therethrough and into the blank spaces immediately below the larger figures indicating dollars, dimes and cents, which memoranda are intended to 30 designate the stations between which the trip is taken and also the fact whether the fare is a regular or half fare. At or near its center, the cutter has a raised or embossed portion e⁴ provided with an opening e⁵ to receive 35 the thumb of the manipulator's right hand which grasps the holder, whereby the cutter can be easily moved or slid upon the tickets in the act of manipulating them.

As stated, the cash fare tickets or slips are 40 separate from each other, that is, in loose form, and a supply thereof is placed in the ticket receptacle C after the cover D has been raised for this purpose, at which time it is desirable to remove the spring ends g from their 45 slots b³. After the device has thus been filled with a supply of tickets the spring is inserted in place and the cover thereby held downwardly upon the supply of tickets with a yielding pressure. When the device is not 50 in use, it is in closed condition, that is, the ticket receptacle is in its telescoped position within the ticket holder proper as far as it will go, as shown in Fig. 1 of the drawings. When the conductor desires to execute a 55 ticket he grasps the holder proper in one hand and draws the ticket receptacle and the supply of tickets outwardly with the other hand, whereupon the parts assume the relative position illustrated in Figs. 2, 6 and 7. At this 60 time, the tickets are brought to a proper position to be acted upon by the sliding cutter E, the larger or more conspicuous figures representing dollars, dimes and cents registering with the notches of such cutter and being exposed 65 at such notches as the cutter is slid

therewith. Taking for an illustration the example shown in Fig. 2 of the drawings wherein a cash fare of \$2.85 has been paid, the conductor moves the sliding cutter by means of the thumb of the hand holding the ticket holder proper until the upper notch e exposes the figure 2, indicating dollars. With the other hand he will raise the upper corner of the uppermost ticket, drawing the same towards the cutter and causing the latter to sever the ticket along the straight edge and into the upper notch. This tearing operation is now interrupted until the cutter is moved so that the other notch e¹ will expose the figure 8 in the series 70 of figures indicating dimes, whereupon the tearing operation is continued but again interrupted until the cutter is moved so that the same notch e¹ is moved to expose the figure 75 5 in the series of figures indicating cents. 80 The tearing operation is again continued and the passenger's receipt now wholly torn off and handed to the passenger. This receipt will indicate by means of the three tips the exact amount of fare thus paid to the conductor. It will be observed from an examination of Fig. 2 that the extending pairs of 85 points e² at the notches of the cutter form pairs of notches a at the base of the tips of the passenger's receipt, with the result 90 that even if the tips by accident or otherwise should become torn off or detached the receipt would still unalterably indicate the exact amount of fare paid, inasmuch as said small notches a coöperate with the other similar but less conspicuous series a¹ of figures 95 indicating dollars, dimes and cents and thereby give exactly the same indication as given by the tips themselves. After the ticket has 100 thus been executed or manipulated by the conductor, the conductor's or auditor's receipt is lying immediately below the cutter and the outer portion of the cover, and when the ticket receptacle and the supply of tickets are moved or telescoped inwardly to 105 closed position, such stub will follow the supply or pile of tickets, inasmuch as such tickets offer a greater resistance than the underside of the cutter. When, however, the ticket receptacle is pulled outwardly for executing the next ticket, the outer or torn edge of said stub will engage against the inner edge of the flange d and will be prevented thereby from following the tickets outwardly 110 and will be retained or deposited in flat form 115 within the ticket holder proper and beneath the cover D, together with all the stubs of tickets subsequently manipulated. It will be understood that this depositing and retaining of the stubs within the holder proper 120 is wholly automatic and is an incident to the telescoping movements of the ticket receptacle, as required for the executing or manipulating of a ticket and the subsequent closing 125 of the device. 130

When the conductor desires to make up his report for the auditor, he removes the wire ends *g* from place and raises the cover, and removes therefrom the stubs which have been deposited therein. The blanks along the bottom edge of each stub are now filled out and punched by the conductor to make a record of the transaction of each ticket. At the same time the memoranda which the conductor had written upon the ticket through the recesses *e* are now transferred to the blanks provided for that purpose along the lower edge or portion of each stub, thereby indicating the stations between which the trip was made in respect to each ticket and the fact whether the fare paid was a regular or a half fare.

I claim:

1. A ticket holder and cutter comprising a ticket holder proper for holding a supply of tickets in flat form, a cutter for manipulating such tickets, and sliding means whereby the stubs in flat form are automatically deposited in the ticket holder proper after the manipulation of the ticket; substantially as described.

2. A ticket holder and cutter comprising a ticket holder, a cutter for manipulating the tickets, means for drawing a supply of tickets partially out of the holder when a ticket is manipulated, said tickets and the stubs being returned to place in the holder after such manipulation, and means for retaining in the holder the stubs of manipulated tickets when the supply of tickets is drawn outwardly; substantially as described.

3. A ticket holder and cutter comprising a ticket holder, a cutter for manipulating the tickets, means for drawing a supply of tickets partially out of the holder when a ticket is manipulated, said tickets and the stubs being returned to place in the holder after such manipulation, and means adapted to engage the severed edge of the stubs of manipulated tickets to retain them in the holder; substantially as described.

4. A ticket holder and cutter comprising a ticket holder, a cutter for manipulating the tickets, means for drawing a supply of tickets partially out of the holder when a ticket is manipulated, said tickets and the stubs being returned to place in the holder after such manipulation, and a strip arranged above the supply of tickets and adapted to engage the severed edge of the stubs of manipulated tickets to retain them in the holder; substantially as described.

5. A ticket holder and cutter comprising a ticket holder, a cutter for manipulating the tickets, means for drawing a supply of tickets partially out of the holder when a ticket is manipulated, said tickets and the stubs being returned to place in the holder after such manipulation, and a strip spring pressed upon the supply of tickets and

adapted to engage the severed edge of the stubs of manipulated tickets to retain them in the holder; substantially as described.

6. A ticket holder and cutter comprising a ticket holder formed in two telescoping parts, one of which is a ticket receptacle receiving and holding the supply of tickets and the other of which is the holder proper into which the stubs are automatically deposited, and a cutter for manipulating the tickets; substantially as described.

7. A ticket holder and cutter comprising a ticket holder formed in two telescoping parts, one of which is a ticket receptacle receiving and holding the supply of tickets and the other of which is the holder proper into which the stubs are automatically deposited, a cutter for manipulating the tickets, and means adapted to engage the stubs to retain them in the holder proper; substantially as described.

8. A ticket holder and cutter comprising a ticket holder formed in two telescoping parts, one of which is a ticket receptacle receiving and holding the supply of tickets and the other of which is the holder proper into which the stubs are automatically deposited, a cutter for manipulating the tickets, and means adapted to engage the severed edge of the stubs to retain them in the holder proper and prevent them from following the supply of tickets when drawn out for further manipulation of tickets; substantially as described.

9. A ticket holder and cutter comprising a ticket holder formed in two telescoping parts, one of which is a ticket receptacle receiving and holding the supply of tickets and the other of which is the holder proper into which the stubs are automatically deposited, a cutter for manipulating the tickets, and a strip arranged above the supply of tickets and positioned in front of the severed edge of the stubs when the device is in closed condition, said strip retaining the stubs within the holder proper; substantially as described.

10. A ticket holder and cutter comprising a ticket holder formed in two telescoping parts, one of which is a ticket receptacle receiving and holding the supply of tickets and the other of which is the holder proper into which the stubs are automatically deposited, a cutter for manipulating the tickets, and a strip spring pressed upon the supply of tickets and positioned in front of the severed edge of the stubs when the device is in closed condition, said strip retaining the stubs within the holder proper; substantially as described.

11. A ticket holder and cutter comprising a ticket holder formed in two telescoping parts, one of which is a ticket receptacle receiving and holding the supply of tickets and the other of which is the holder proper into which the stubs are automatically deposited,

a cutter for manipulating the tickets, and means for holding said two parts of the ticket holder in telescoping relationship; substantially as described.

5 12. A ticket holder and cutter comprising a ticket holder formed in two telescoping parts, one of which is a ticket receptacle receiving and holding the supply of tickets and the other of which is the holder proper into 10 which the stubs are automatically deposited, a cutter for manipulating the tickets, and means for normally limiting the degree of relative movement of said parts so as to bring the tickets in proper position for the 15 action of the cutter; substantially as described.

13. A ticket holder and cutter comprising a ticket holder formed in two telescoping parts, one of which is a ticket receptacle receiving and holding the supply of tickets and the other of which is the holder proper into 20 which the stubs are automatically deposited, a cutter for manipulating the tickets, and means adapted to engage the severed edge 25 of the stubs to retain them in the holder proper and prevent them from following the supply of tickets when drawn out for further manipulation of tickets comprising removable projections in the path of the ticket 30 receptacle; substantially as described.

14. A ticket holder and cutter comprising a ticket holder formed in two telescoping parts, one of which is a ticket receptacle receiving and holding the supply of tickets and 35 the other of which is the holder proper into which the stubs are automatically deposited, a cutter for manipulating the tickets, means for normally limiting the degree of relative movement of said parts, and means for holding 40 said parts in telescoping relationship except when the ticket receptacle is drawn out to an abnormal degree; substantially as described.

15. A ticket holder and cutter comprising 45 a ticket holder formed in two telescoping parts, one of which is a ticket receptacle receiving and holding the supply of tickets and the other of which is the holder proper into which the stubs are automatically deposited, 50 a cutter for manipulating the tickets, means for normally limiting the degree of relative movement of said parts, and means for holding said parts in telescoping relationship except when the ticket receptacle is drawn out 55 to an abnormal degree, such means comprising inturned flanges on the ends of the holder proper under which the ends of the ticket receptacle slide, said ends of the ticket receptacle being recessed at one point to permit 60 the same to be removed from the holder proper when such receptacle is drawn out to an abnormal degree; substantially as described.

16. A ticket holder and cutter comprising 65 a ticket holder formed in two telescoping

parts, one of which is a ticket receptacle receiving and holding the supply of tickets and the other of which is the holder proper into which the stubs are automatically deposited, a cover pivoted to said holder proper, and a 70 cutter located at one edge of such cover for manipulating the ticket; substantially as described.

17. A ticket holder and cutter comprising a ticket holder formed in two telescoping 75 parts, one of which is a ticket receptacle receiving and holding the supply of tickets and the other of which is the holder proper into which the stubs are automatically deposited, a cover pivoted to said holder proper, and a 80 cutter located at one edge of such cover and adapted to move thereon for manipulating the ticket; substantially as described.

18. A ticket holder and cutter comprising a ticket holder formed in two telescoping 85 parts, one of which is a ticket receptacle receiving and holding the supply of tickets and the other of which is the holder proper into which the stubs are automatically deposited, a cover pivoted to the outer edge of said 90 holder proper, and a cutter located at one edge of such cover for manipulating the tickets, said cover and cutter being pressed with a yielding pressure towards the supply of tickets; substantially as described. 95

19. A ticket holder and cutter comprising a ticket holder formed in two telescoping parts, one of which is a ticket receptacle receiving and holding the supply of tickets and the other of which is the holder proper into 100 which the stubs are automatically deposited, a cover pivoted to the holder proper, and a cutter arranged to move along one side of the cover, said cover having a depending flange located along that side adjacent the cutter 105 and bearing upon the supply of tickets to engage the severed edges of the stubs and retain them in the holder proper; substantially as described.

20. A ticket holder and cutter comprising 110 a ticket holder formed in two telescoping parts, one of which is a ticket receptacle receiving and holding the supply of tickets and the other of which is the holder proper into which the stubs are automatically deposited, 115 a cover pivoted to the holder proper to overlie the supply of tickets and provided along one side with a depending flange, said cover being spring-pressed to cause its flange to bear upon the supply of tickets to engage the 120 severed edges of the stubs, and a cutter adapted to move upon said side of the cover; substantially as described.

21. A ticket holder and cutter comprising 125 a ticket holder formed in two telescoping parts, one of which is a ticket receptacle receiving and holding the supply of tickets and the other of which is the holder proper into which the stubs are automatically deposited, a cover pivoted to the outer edge of said 130

holder proper, a cutter located at one edge of such cover for manipulating the tickets, and a spring coöperating with such cover to hold it together with the cutter spring-pressed towards the supply of tickets; substantially as described.

22. A ticket holder and cutter comprising a ticket holder formed in two telescoping parts, one of which is a ticket receptacle receiving and holding the supply of tickets and the other of which is the holder proper into which the stubs are automatically deposited, a cover pivoted to the outer edge of said holder proper, a cutter located at one edge of such cover for manipulating the tickets, and a spring coöperating with such cover to hold it together with the cutter spring-pressed towards the supply of tickets, the ends of the spring being inserted into the ends of the holder proper and in the path of movement of the ticket receptacle to serve as a stop to limit the degree of outward movement of the latter; substantially as described.

23. A ticket holder and cutter comprising a ticket holder formed in two telescoping parts, one of which is a ticket receptacle receiving and holding the supply of tickets and the other of which is the holder proper into which the stubs are automatically deposited, a cover pivoted to the outer edge of said holder proper, a cutter located at one edge of such cover for manipulating the tickets, and a spring coöperating with such cover to hold it together with the cutter spring-pressed towards the supply of tickets, the ends of the ticket receptacle having flanges and the ends of the spring being inserted into the ends of the holder proper and in the path of movement of said flanges; substantially as described.

24. In a ticket manipulating device, the

combination, with the ticket holder, of a cutter having a straight edge and provided with a severing notch within the line of the straight edge and two projections adjacent 45 said notch and extending beyond the line of the straight edge; substantially as described.

25. In a ticket holder and cutter, the combination of a holder proper adapted to hold a supply of tickets, and a cutter adapted to 50 move in relation to the holder and upon the supply of tickets, said cutter having a slot which exposes a portion of the uppermost ticket and through which the manipulator is enabled to write data; substantially as de- 55 scribed.

26. In a ticket holder and cutter, the combination of a holder proper adapted to hold a supply of tickets, and a cutter adapted to move in relation to the holder and upon the 60 supply of tickets, said cutter having two slots in alinement which expose portions of the uppermost ticket and through which the manipulator is enabled to write data; sub- 65 stantially as described.

27. In a ticket holder and cutter, the combination of a holder proper adapted to hold a supply of tickets, and a cutter adapted to move in relation to the holder and upon the supply of tickets, said cutter having at or 70 near its center a raised portion provided with an opening to receive the thumb of the manipulator in operating the cutter, and also having on each side of said raised portion longitudinal slots which expose portions 75 of the uppermost ticket and through which the manipulator is enabled to write data; substantially as described.
